UNITED STATES PATENT OFFICE.

CARL E. NAGEL, OF ST. PAUL, MINNESOTA.

REINFORCED-CONCRETE PILING.

1,340,397.

Specification of Letters Patent. Patented May 18, 1920.

Application filed December 10, 1917. Serial No. 206,454.

To all whom it may concern:

Be it known that I, CARL E. NAGEL, a citizen of the United States, residing at St. Paul, in the county of Ramsey and State of Minnesota, have invented certain new and useful Improvements in Reinforced-Concrete Piling, of which the following is a specification.

My invention relates to reinforced concrete piling and the method of forming the same and has for its object to provide pile members constructed of reinforced concrete which shall be of light weight and so fabricated that such members can be driven in association so as to provide a composite pile of large size and any depth of bearing desired, or to provide forms of abutments and retaining walls for bridge heads or culverts involving small stream crossings.

In carrying out my invention I provide pile members of such cross-sectional area that a desired number in combination may form a more extended pile member of cross-section substantially circular, and further that the sections may be driven and united during driving to provide piling of any desired length, while the sections themselves are sufficiently short to be of comparatively light weight. Sections can be fabricated at some central depot and shipped ready for driving, and are sufficiently small so that they may be readily handled with ordinary loading apparatus. The several sections are driven separately and therefore a light driving apparatus such as small road-making organizations possess is sufficient to drive the sections. Yet, when the completed pile is driven it will be of very massive and powerful construction and have as great a bearing as may be desired.

It is a further object of my invention to provide a novel form of assembling the pile member sections to produce completed piles of large cross section and extent as above outlined. Other objects of my invention consist in the provision of bridge supports and abutments of novel and meritorious construction.

The full objects and advantages of my invention will appear in connection with the detailed description thereof and are particularly pointed out in the claims.

In the drawings, illustrating an application of my invention in one form—

Figure 1 is a side elevation with some

parts in section of a single pile member. Fig. 2 is a diagrammatic illustration of the manner in which pile member sections are assembled. Fig. 3 is a transverse section of one of the pile members. Fig. 4 is a sectional view on line 4—4 of Fig. 1. Fig. 5 is a side elevation view partly in longitudinal section of the device for assembling and driving the piling. Fig. 6 is a sectional view on line 6—6 of Fig. 5. Fig. 7 is a sectional view on line 7—7 of Fig. 5. Fig. 8 is an elevation view with some parts broken away showing complete composite piles in position and the manner in which cross beams are cast upon the same to form bridge bents. Fig. 9 is a sectional view on line 9—9 of Fig. 8. Fig. 10 is a side view of a portion of a bridge in position upon pile bents such as shown in Fig. 8. Fig. 11 is a top plan view showing the manner of assembling pile members to form an abutment. Fig. 12 is a part sectional elevation view taken on line 12—12 of Fig. 11. Fig. 13 is a part fragmentary end elevation of an abutment bridge head. Fig. 14 is a sectional view on line 14—14 of Fig. 13. Fig. 15 is a sectional elevation through one of the piles as shown in Fig. 13. Fig. 16 is an enlarged sectional view taken on line 16—16 of Fig. 13 showing how displacement of the piles in driving an abutment head is compensated so that notwithstanding displacement the pile members coöperate and form a closed head. Figs. 17 and 18 are sectional elevation and plan of a small bridge or culvert supported upon an end wall abutment resting on a pile member tier constructed from pile sections in accordance with my invention.

As shown in Figs. 1 and 3, I provide pile members 20 which are substantially triangular in cross-section, preferably being formed with a front wall 21, side walls 22 and a very short inner apex wall 23. Cast within the pile member 20 are a series of steel reinforcing rods, there preferably being three of said rods 24, 25 and 26, the rod 24 being adjacent the apex angle or side of the pile member and the other rods being adjacent the two front side angles. At the lower end of the point section the rods 25 and 26 are bent inwardly as indicated at 27 in Fig. 1 and are brought into alinement with the apex rod 24 as indicated at 28, preferably being wound with wire 29 to hold them together. The point end is

provided with a slanting wall 30 which extends obliquely from the front wall 21 to the apex wall 23 of the section and which is preferably dished or spooned out, as indicated at 31 in Figs. 1 and 4. A driving point is thus formed at the junction of the wall 23 with the sloping wall 30 which is strongly reinforced by the massed metal at 28, 29. The sloping shovel-like side of this driving point tends continually to force the pile member inwardly for a purpose which will later be described.

Normally the rods 24, 25 and 26 are projected beyond the lower end 32 of a pile member as indicated at 33 in Fig. 2 and the rods 24, 25 and 26 do not reach the upper end 34 of the pile member but are seated in pipes or socket members 35, which thus provide apertures 36 in alignment with the rods 24, 25 and 26. The projecting portions 33 of these rods enter the apertures 36, there preferably being a washer 37 of some shock-absorbing material positioned between the ends 32 and 34 of the pile sections and through which the rod projections 33 extend, this washer being to prevent shattering of adjacent sections during driving.

One special use of my pile members is to provide large heavy piles out of an-assemblage of the pile member sections for forming bents or bridge supports for extended or heavy bridges, and the method of fabricating and driving such piles from my sectional members constitutes one of the features of my invention. In general the pile members 20 are comprised of such cross-sectional area that a given number of them may be assembled with adjacent walls in contact and thereby produce a pile member substantially cylindrical in form or one having a cross-sectional outline of an equilateral polygon. In the form shown eight of the members driven with adjacent walls in contact will coöperate to form an eight-sided pile. The method of driving such a piling consists in providing a central member 40, such as a pipe, supporting in surrounding relation to said pipe a framing 41 in which the inside cross-section is a polygon similar to that of the pile to be completed, and subsequently driving in the proper order various pile members about the central member and within the framing until the composite pile is fully completed, and then withdrawing the central member and filling the same with concrete as it is withdrawn. In practice the central member 40 consists of a four-inch pipe which is driven in advance, water being forced through the pipe to open the way in advance of the pipe and keep it free from dirt and stones and permit accurate vertical positioning of the pipe to the desired depth. The framing 41 may be composed of steel, wood or any suitable material

and is supported at its lower end upon the ground where the piles are to be driven, and at its sides by encircling frame members 43, 44 and 45. The framing is held in proper vertical position by means of guys 70 46 attached to some or all of the frame members 43, 44 and 45. In some kinds of soil it may be practicable to drive all or a part of the piles with conical points as indicated at 48 in Figs. 5 and 8. The oblique points 75 are, however, best adapted to most soils as they cause the pile to cling to the central pipe 40 and in effect shovel the earth away from said central member. Where conical points are employed it would be preferable 80 for the first four pile sections, driven at alternately separated positions, to be followed by the driving of piles with oblique points driven in between those having conical points, all as indicated in Fig. 8. The 85 framing 41 is of such length as to hold one complete set of sections, which as indicated in Fig. 7 are in position within the framing before any driving is done, and which when so positioned operate to guide the central pipe 40 as the same is driven. A follower 49 formed of steel or other suitable material is provided at its lower end with a resilient buffer head 50 and with pins 51 which enter the apertures 36 in the upper 90 ends of the pile members 20, thus uniting the driving follower 49 with such pile member. The follower 49 as shown in Fig. 6 is of the same cross-sectional dimensions as the pile sections 20. A hasp 52 is secured to the follower 49 and has a portion 53 which encircles the central pipe 40, thereby holding the follower in alignment with the central pipe as the same is driven down after one of the sections. In place of attaching the hasp 105 52 to the follower and having it slide upon the pipe, such a hasp may be, if desired, secured in rotative position to the central pipe and the driving follower may slide within the hasp. In practice the point sections are first driven through the framing 41 in the order indicated in Fig. 7 by the letters *a*, *b*, *c* and *d*, and then *w*, *x*, *y* and *z*. That is, in each instance the sections are 110 successively driven at diametrically opposite 115 positions from that of the section which has just been driven. This further insures that each section as it is driven is supported during the major portion of the driving period by adjacent sections. That is, sections *a*, *b*, *c* and *d* as they are driven are laterally supported by adjacent sections within the framing, while the sections *w*, *x*, *y* and *z* are laterally supported by adjacent sections below the framing and in 125 the ground. The various sections are thus constrained to move in proper vertical direction and in proper relation to one another into their final position. When one set of sections has through operation of 130

the follower been driven down to the limit of drive within the boxing 41, another set of sections is assembled upon the first set by introducing the extended portions 33 5 of the rods 24, 25 and 26 at the lower ends of such members into the apertures 36 in the upper ends of the driven members with a shock-absorbing washer 37 between said ends. A full set of such members is of 10 course placed in position and the follower 49 is then used to drive the members in the order *a*, *b*, *c*, *d* and *w*, *x*, *y*, *z* above referred to, thus insuring that at all times each pile member as it is driven is laterally supported 15 for a major portion of its driving distance by adjacent pile members. The upper section being driven is also supported on its outside face by the framing box 41, and all of the sections are supported on 20 their inside faces by the pipe 40 against which they may be caused to tend to move by reason of the sloping shovel point at the end of the point section.

After all of the sectional members have 25 been driven down to a suitable bearing point, and, as illustrated in Fig. 8, it is best to have a part of the members extended somewhat lower than another part so as to break joints, the pipe 40 which has been 30 sunk by flowing water through the same is gradually withdrawn and grout or soft concrete is driven through it as it is withdrawn, filling up the opening thus left with a core 59 of concrete which serves as a means of 35 cementing or uniting together the various pile members so that the composite pile will be integrated and act as a unitary structure.

The result of this operation is a completed pile 60, best shown in Figs. 8 and 40 10, which is of large size and having a high degree of bearing pressure which is secured by a comparatively small driving device, since the individual pile members are of course of comparatively small section 45 and therefore may be driven to a high bearing resistance by a small driver. In practice the portion of the piles 60 which is above water and ground level, and in fact which extends a short distance below 50 such level, is covered with a wire mesh as indicated at 61 in Fig. 8, and cement plastered upon it to make a smooth united surface, which with the core 59 has the effect of completely uniting the pile members. A portion of some only of the pile 55 members, as indicated in dotted lines at 62, extends above the top of the others, and concrete beams 63 are cast upon the ends of the piles so as to embrace such extended members. In this manner a pair 60 of piles 60 with the concrete 64 surrounding them and a connecting beam 63 constitutes a bridge bent upon sets of which the bridge slab 65 is directly supported. 65 A bridge so constructed may be made of

any weight or height for practical highway purposes and will be in all respects strong and enduring.

My sectional pile members may also advantageously be used to produce a continuous pile wall bearing for abutments, bridges of short span and similar purposes, as indicated in Figs 11 to 18 inclusive. In setting such piles a framing is provided consisting of sets of beams 70 75 and 71 spaced apart a distance sufficient to receive a single pile member between them and a second set of beams 72 and 73 similarly spaced, all being held by wooden pile members and braces 74, 75, 76. The 80 pile members 20 are positioned in a row as indicated in Fig. 11 and the follower 49 is operated in alternation upon said pile members to drive them into the ground a distance sufficient to secure a desired degree of bearing resistance, succeeding sections being positioned as the piles are driven, so that at all times a pile being driven will have lateral support from other piles throughout a major portion of its 85 length and will have front and back support from the frame members 70, 71 and 72, 73. If during the driving any of the pile members become displaced, as indicated in Fig. 16, the intervening members 90 95 will tend to take positions in engagement with the adjacent members. For instance, if members designated as 75, 76 and 77 in Fig. 16 are driven so that members 75 and 76 become spaced a little too far and 100 76 and 77 become spaced a little too close, a member 78 may have its tapered portion projected beyond the rear line of members 75, 76, 77 and a member 79 may correspondingly project at its forward portion so that the sides of all of the members will still remain in contact, the intervening members such as 78, 79 being provided with inwardly-sloping shovel points.

A series of pile members driven as indicated may form supporting and wing abutments 80, 81 upon which a retaining wall 82, 83 may be constructed for directly supporting the bridge slab 84, or the piles may extend upwardly as indicated at 85 115 in Fig. 17 so as themselves to form the retaining wall and directly support a series of slabs 86. Such a small bridge or culvert has many advantages in that if it is desired at any time to lower the water line 120 under the bridge, which is sometimes required by ditching or other changes in the drainage system of a given region, this can be done without in any respect interfering with the design or efficiency of the 125 bridge structure. This is clearly illustrated in Fig. 17, where the original bottom of the stream is indicated at 90 and a lowered bottom by dotted lines at 91.

The various advantages of my invention 130

have been quite fully pointed out in the detailed description thereof. It will be clear, however, that the pile member units herein described may be fabricated at a central factory and will not individually be difficult to ship and handle, requiring no heavy hoisting mechanism, nor heavy driving mechanism for setting, such as has greatly limited the general use of concrete piling as heretofore designed. It is a fact that the majority of highway bridges are constructed by county or township organizations which do not have available the heavy type of machinery necessary for the handling and setting of concrete piles. At the same time the desirability of concrete pile support for all forms of road bridges is universally conceded. In the practice of my invention it is possible for county and township organizations to set concrete piling of large cross-section, and to any desired point of bearing resistance, with the use of such light hoisting and driving machinery as is ordinarily in the possession of or available for the use of such organizations. An additional very great advantage of my composite pile and method of setting the same resides in the fact that the two pile members in line with a bridge bent such as members *d* and *c* or *a* and *b* of Fig. 7 may be extended above the tops of the other members and a narrow, deep beam directly cast to include these extensions, which act to resist any twisting or tipping stresses upon such a beam. In this way the beam does not need to be any thicker than the diameter of the pile, which gives not only an effective construction for supporting the necessary load, but one which is exceedingly neat in appearance.

I claim:

1. A pile member comprising a concrete shaft of generally triangular cross-section, reinforcing rods extending longitudinally through said member adjacent the angular limits thereof, said pile being provided with a point by having its end formed slanting from one side of the member toward an angle thereof and said reinforcing rods extending into and being joined together adjacent said point.
2. A pile comprising a multiplicity of longitudinal sections each consisting of a plurality of members held in longitudinal alinement and a central core united with all of said members.
3. A composite pile comprising a multiplicity of longitudinal pile sections having adjacent contacting faces and forming together a pile member of substantially circular cross section, each of said longitudinal

sections consisting of a plurality of reinforced concrete members extending in alinement united at their adjacent ends.

4. A composite pile comprising a multiplicity of longitudinal pile sections having adjacent contacting faces and forming together a pile member of substantially circular cross section, each of said longitudinal sections consisting of a plurality of reinforced concrete members extending in alinement united at their adjacent ends, and a central core of concrete uniting all of said sections.

5. The process of forming composite piles which consists in assembling a multiplicity of pile sections with adjacent walls in contact, said sections being of such shape as to produce a complete pile member of the desired outline, holding the noncontacting faces of said members, and driving the members separately and in alternation so that each member is supported by adjacent pile members during the major part of its movement in being driven.

6. The process of forming composite piles which consists in assembling a multiplicity of pile sections with adjacent walls in contact, said sections being of such shape as to produce a complete pile member of the desired outline, holding the noncontacting faces of said members, driving the members separately and in alternation so that each member is supported by adjacent pile members during the major part of its movement in being driven, assembling additional sets of pile sections upon the ends of those already driven, and driving said new sets of sections in the same manner as the preceding sections were driven.

7. The process of forming extended composite piles which consists in introducing a hollow member to a depth in the ground to which it is desired that the pile shall extend, assembling a multiplicity of pile sections about and in contact with said hollow member, said pile sections being of such shape that when so assembled their adjacent walls will contact and form a pile of the desired circumferential outline, driving the pile sections separately, adding other sets of pile sections and driving them separately in the same manner, continuing such operation until all of the composite sections have reached a depth for securing a desired degree of pressure bearing, withdrawing the hollow member, and filling the opening left by the hollow member with grout or concrete to form a uniting core for the composite pile.

In testimony whereof I hereunto affix my signature.

CARL E. NAGEL.
